PROCESS AND APPARATUS FOR FORMING
THE HEEL SEAT OF A SHOEArthur J. Brauer and Frederick P. Wagner,
St. Louis, Mo.Application December 15, 1930
Serial No. 502,343

20 Claims. (Cl. 12—31.5)

This invention relates to the art of making shoes, and more particularly to method and means for preparing the heel seat of the shoe. This invention is particularly applicable to ladies' shoes employing high heels, although many of the features of this invention are applicable to foot-wear generally. In the description which follows the term "shoe" will be employed to cover and comprehend a boot as well as a shoe.

10 In the manufacture of shoes, and more particularly ladies' shoes employing wood heels, it has been the practice to concave the seat of the heel in order that the margin of the heel where it engages the upper at the heel seat may form a close joint having the desired attractive appearance. This upper at the heel seat is lasted over counter and the insole, where employed, and over-lying the heel seat is an extension of the outsole. It is the practice to marginally recess 15 the sole extension at the heel seat, although the line of stitches attaching the sole to the upper extends at least to the breast of the heel when positioned on the shoe. Since the seat of the heel itself is concave, as described above, it has also been the practice to chamfer the rear extension of 20 the sole so as to give it a somewhat convex formation in order to conform to the concave seat of the heel, to a degree at least.

It is desirable that there be shoulders formed 25 at the ends of the marginal recess terminating at the heel breast, even where a wooden "Louis" heel having a forward extension is employed. Accordingly, it is the practice, after the formation 30 of the heel seat by marginally recessing and chamfering, to position the heel on the shoe, to mark the breast line thereon and then to trim the sole margins at the ends of the breast line; whereby when the sole is finally positioned on the 35 shoe, the sole edges will form in effect a continuation of the heel.

These operations on the heel sat of the lasted upper with the sole applied, have heretofore 40 usually been performed by hand, particularly where the marginally reduced sole portion at the heel has been tacked in place before such chamfering or convexing of this extension. It is desirable and practically essential for the production 45 of a well-made and artistic shoe, that this sole extension at the heel seat be not left loose, for otherwise a proper fit cannot be secured; furthermore, the line of stitches attaching the sole to the shoe extends at the time at least up to the 50 breast line. It will be understood that this heel fitting operation is an individual operation for each shoe; for although the heels may be made

alike, this is not true of the heel seat on the lasted and soled upper. Accordingly, in practice a shoe heel seat is, after marking of the breast line thereon, trimmed and convexed so that it will conform to a heel for that shoe, and this heel is placed on the rack alongside of the shoe for subsequent attachment. It will be seen that this is not only an expensive operation, since it must be performed by hand, but unless performed skillfully and by skillful operators, the desired artistic appearance is not secured.

In application Serial No. 372,845, filed June 22, 1929, there is described means whereby the heel end of the sole is marginally reduced, so as to not only conform to an extent to the concavity of 70 the heel, but also to provide shoulders at the breast line against which the breast of the heel may abut. Unless, however, the cutting mechanism for marginally reducing the heel end of the sole is of a form to chamfer the edges of the extension, it is necessary to resort to chamfering, unless the cutting mechanism is of such a construction as to perform such chamfering, or unless the heel seat is formed with a depression 75 conforming to the extension. The former, however, requires a rather complicated mechanism, while the latter requires a special recessing of the heel seat of the heel, which also involves additional cost and complication of mechanism. Moreover, the mere marginal reduction of the 80 heel end of the sole still requires that the breast portion of the heel seat between the shoulders simply rest on the extension along the breast line. This will not provide the desired snug fit even 85 where the heel is firmly clamped and cemented 90 to the shoe.

One of the objects of this invention, therefore, is to provide method and means for forming the heel end of a shoe, in which the operations are so performed that the extension will conform to 95 the concavity of the heel seat.

Another object is to provide method and means whereby a shoulder is formed on the sole along the breast line and against which the breast portion of the heel may snugly fit.

Further objects will appear from the detail description taken in connection with the accompanying drawings and in which will be illustrated embodiments of this invention. It will, however, be understood that this invention is susceptible 100 of various embodiments within the scope of the appended claims.

In the accompanying drawings, Figure 1 is a perspective view of a shoe with its attached sole; Figure 2 is a bottom view of the heel end of the 110

shoe, illustrating the marginal reduction at the heel seat, adapted more particularly for a so-called "Cuban" heel;

Figure 3 is a similar view showing the formation 8 of the sole extension and the shoulder along the breast line where the latter is straight;

Figure 4 is a view similar to Figure 3, showing the formation of a curved breast line;

Figure 5 is a side elevation showing the "Cuban" heel in place;

Figure 6 is a view similar to Figure 3, showing the formation of the heel end of a sole adapted to receive a "Louis" heel;

Figure 7 is a view similar to Figure 5, showing a 16 "Louis" heel in place;

Figure 8 is a perspective view showing cutting mechanism for marginally reducing the heel seat;

Figure 9 is a side elevation showing mechanism for forming the heel seat and the shoulder along 20 the breast line;

Figure 10 is a bottom view of a die as employed in the mechanism of Figure 9;

Figure 11 is a sectional view, showing the operation of this die; the section being taken along 24 the shoe;

Figure 12 is a section on the line 12—12 of Figure 11; and

Figure 13 is an enlarged detail of Figure 12.

Generally stated, in accordance with this invention, the heel end of the sole is preferably but not necessarily reduced marginally. This may be accomplished by hand or by mechanism of the general character disclosed in said application and also shown in Figure 8. The shoe is then placed in suitable mechanism whereby the formation of the heel end of the sole is completed. This is preferably accomplished by a suitable die, whose formation corresponds to that desired. This die will serve to not only conform the sole 28 extension to the concavity of the heel, but also to press down the turned over edges of the upper surrounding the extension. The die also operates to form a definite shoulder along the breast line across the entire sole and against which the breast 32 portion of the heel may abut. In accordance with this invention, the operations are accomplished by combined action of pressure and heat; the heat being applied during the pressing operation performed by the die. This serves not only to conform the sole extension to the concavity of the heel seat, but also to give the same a permanent set. Furthermore, the turned in edges of the upper are also given a pressing, as well as an ironing, operation under the combined action of pressure and heat, so as to provide a firm and accurately formed seat along the margin of the heel and outside of the extension on which the heel will have a snug fit. The manner of accomplishing these operations will be hereafter more 36 particularly described.

Referring now to the accompanying drawings, 1 designates the upper of a shoe which is mounted on a suitable last 2, and provided with a sole 3, having the usual extension 4, while the turned over edges of the upper at the heel seat are shown at 5. In order to locate the breast line, the heel is positioned on the shoe and the breast line marked, as shown by the line 6. The heel end of the sole is now subjected to the action of the die, 40 as hereinafter described, in order to reduce the same marginally and particularly to form shoulders 7 at the breast line.

The operation of marginally reducing the sole 44 may be performed by mechanism shown in Figure 8, and more particularly described in the

application referred to. It comprises a pair of cutters 8 adapted to enter the crease between the sole and the upper adjacent and back of the breast line, with cooperating cutters 9, adapted to cut through the sole while supported by the cutters 8. The cutters 8 and 9 are arranged in sets supported on posts 10 and 11, mounted on a base 12; the post 11 being guided on the base by a suitable guide 13 for movement towards and from the post 10, and this movement being secured by a suitable lever 14. Each of the cutters 8 is secured directly to its post; however, the cutter 9 is mounted on a block 15 guided for vertical movement on the post and normally held in raised position by springs 16. In practice, the mechanism shown in Figure 8 is mounted on a suitable press, the ram of which engages blocks 15, so as to depress the cutters 9 to cooperate with the cutters 8.

The mechanism described and shown in Figure 8 is fully described in the application referred to. In order to perform the operation of marginally reducing the sole, the shoe is placed with the cutters 8 within the crease and with the breast line, previously marked, located by the 95 forward edges of these cutters. These cutters in the particular embodiment shown in Figure 8 are shaped to form a curved breast line of the character shown in Figure 4, although it is obvious they may be conformed to a breast line as 100 shown in Figure 3. After the shoe has been positioned and the post 11 moved inwardly, so that the cutters 8 will be well within the crease, and, in fact, arrested by the lines of stitching securing the sole to the upper, the cutters 9 are caused 105 to move down to cooperate with the cutters 8, in order to cut through the sole edges and marginally reduce the sole, as well as to form the shoulder 7.

The next operation is one to conform the sole 115 extension 4 to the concavity of the heel seat, as well as to form a shoulder 17 along the breast line. For this purpose a die 18 is provided. This die has a recessed portion 19 conforming to the extension 4, but curved transversely and longitudinally, as shown in Figures 10, 11 and 12, in order to conform to the concavity of the heel seat. Surrounding the recess 19 is a recess having side portions 20 and a back portion 21. These portions are so shaped as to engage the turned over edges of the upper surrounding the marginal extension, in order to shape and press the latter. Outside of the recesses 20—21 is a flat 125 face 50, and the recess 20—21 merges into that face.

The die is provided with ribs or extensions 22, so that it may be detachably mounted in a suitable ram 23, Figure 9, in order that dies of any suitable shape or construction corresponding to the particular shoe or range of sizes and widths of shoes under consideration. This ram is mounted to reciprocate in a guide 24 acted upon by any suitable mechanism, such as a toggle 25 and an eccentric 26 on a shaft 27, provided with a suitable clutch (not shown). This clutch may 135 be of the type well-known in the prior art, in which upon manipulation of a treadle 39, the toggle will be straightened and then come to rest, while upon the succeeding manipulation, the toggle will become broken and again come to 140 rest.

A suitable support for the last is shown at 28. This support is mounted for vertical movement in the bed 29 of the frame and rests upon a spring 30, compressed between the support and 150

an abutment 31 in the frame. A stem 32, attached to the support 28, passes through the abutment and is provided with a hand nut 33, arranged to engage a stop 34 on the abutment.

5 Suitable heating means is provided for imparting heat to the die. This heating means may be of any desired form; the purpose being to maintain the die at the desired temperature. In the embodiment shown, the ram 23, which receives 10 the die, or the die itself, may be provided with an electrical heating element 35, controlled by a switch 36.

After the sole end of the shoe has been marginally reduced, for instance, by the mechanism 15 shown in Figure 8, and previously described, it is subjected to the action of the die, Figures 9-12. For this purpose the last is placed on the support 28 and the shoe adjusted with the extension 4 within the recess 19 and with the breast line 20 6, Figure 1, aligned with the forward edge 60 of the die. Heat having been previously applied to bring the die to the desired temperature, the clutch is now shifted so as to cause straightening of the toggle 25. This will force the die 25 against the heel seat, so as to place the same under the combined action of pressure and heat. This pressure and heat will not only serve to shape the extension 4, giving it the desired concavity, as shown in Figure 12, but the forward 30 edge 60 of the die will sink into the sole so as to form along the breast line a definite depression, in order to provide a definite shoulder 17 at the breast line and as a continuation of the shoulder 7. Moreover, the flat face 50 will serve 35 to shape the turned over edge of the upper, in order to provide a seat, while the portions 20 and 21 will take care of the otherwise wrinkled edges of the upper. Since the shaping of the seat 40 margin is secured by the flat face 50, a single die can be used for shoes and heels of quite a number of sizes and widths.

As the heel seat is left under the combined action of pressure and heat for some time, not 45 only will such shaping be secured, but a permanent set will also be imparted to the sole and the turned over edges of the upper, in order to provide the desired seat for the heel. After the operation has been completed to the desired extent, the clutch is again shifted so as to break the 50 toggle and the shoe can be removed. It will be noted that the shoe is subjected to the action of the die while under a yielding pressure determined by the spring 30, whose tension can be 55 predetermined. The adjustment of the hand wheel or nut 33 determines the upper position of the support, so as to adapt the machine, Figure 9, to shoes of different sizes, as well as to determine to an extent the tension of the spring.

After the heel seat has been completed in the 60 manner described, the heel 40 is placed thereon and secured in any suitable manner, as by a screw and glue or other suitable fastening means. The heel can be readily located; but not only does shoulder 7 secure such location, but the shoulder 65 17 definitely determines the breast line against which the breast portion of the heel may abut.

Figures 6 and 7 show the application of this 70 invention to the formation of the heel seat designed for a "Louis" heel. In this case the marginal extension 4 is extended; however, the operations are substantially the same as previously described. To this heel seat can be applied a "Louis" heel 41, and here again, the shoulder 75 17 serves to definitely locate the forward exten-

sion 42 of the heel, while the flap 43 can be cemented against the breast in the usual manner.

It will therefore be seen that in accordance with this invention there are applied to the heel seat a forming pressure and heat, which, however, have the following distinguishing characteristics: a localized heavy forming pressure and high heat are applied so a narrow band on the outside margin of the upper where it turns over, and this application of pressure and heat is to an extent and at a temperature sufficient to form and set the upper along that narrow band for the reception of the margin of a heel. This pressure is particularly heavy and localized for the reason that the part 50 of the die face (Figs. 10, 11, 12, and 13) is relieved to form a recess 20-21. This band or rim is generally indicated in Figure 10 as that part extending between the construction line 51 and the line 52. Inside of the line 52, the slightly hollowed out zone 20-21 operates on the inside plaited margin of the turned-over upper to press down and flatten the plaits; accordingly, there will be generally applied a heavy localized pressure along that narrow band so as to provide a shaped seat for the rim of the heel, which in a wooden heel is rather narrow, even when the leather covering is turned in, as even in such a case there is provided a narrow marginal rim. Where an outsole has a part overlying the heel seat and where that part is marginally reduced, a heavy forming pressure will be applied to that part so as to convex the same and particularly to operate on the margin of that part, as shown in Figures 11 and 12. The forward part of the die sinks into the sole part along the breast line so as to provide a distinct shoulder 17 extending along the breast line and in line with the shoulders 7 (Figures 3, 4 and 6) in order to provide a shoulder or abutment for the breast of the heel. The pressure to which the heel seat is subjected is a heavy forming pressure as distinguished from simply an ironing contact, and the extent of this pressure will, of course, depend upon the size of the shoe and the material being operated upon. Where the shoe is of the character as previously described, it has been found that a total pressure applied to the die of about twelve hundred (1200) pounds secures satisfactory operation. The heat applied is a high heat as distinguished from simply a light searing heat, and the temperature must be sufficient to secure, in connection with a high forming pressure, a setting of the material under the combined action of pressure and heat. While, again, the temperature may vary somewhat in accordance with the material being operated upon, in the case of a shoe of the character previously described, a temperature at the heel seat of about 300° F. has been found to be 105 satisfactory.

It will thus be seen that the invention accomplishes its objects. Means is provided whereby the heel seat may be accurately formed to conform to the heel. Not only is the reduced extension shaped to conform to the concavity, but the turned in margins of the upper are shaped to conform to the margins of the heel at the heel seat. Where such a heel is covered with leather, as is usually the case, this leather will extend underneath the heel seat, and as it is accurately formed in its manufacture, and since the margin of the heel seat on the shoe has been accurately formed and shaped, there will be a snug joint between the heel and the shoe around the 110 115 120 125 130 135 140 145 150

entire heel seat margin. The formation of the shoulder across the entire sole will not only serve to locate the breast portion of the heel and provide a firm abutment, but where, as in the "Cuban" heel, the joint of the breast is exposed, there will be no gap at the breast. Even where a "Louis" heel is employed, the shoulder will be of advantage, for the depression will take care of the substantial thickness of the extension 42 at its tip, so that there will be a smooth continuation of the flap 43 as it passes over the sole to the extension and the breast.

While this invention is particularly applicable to shoes having the general types of heels shown and described, it will be understood that this invention is applicable in many cases to other forms and types of heels. It is further applicable to shoes having soles and bottoms of different types and attached by various means, whether by stitching, cement or even by metallic fasteners. It will furthermore be understood that certain features, operations and sub-combinations are of utility and may be employed without reference to other features, operations and sub-combinations; that is contemplated by and is within the scope of the appended claims. It is moreover obvious that various changes may be made in the details of operations and constructions within the scope of the appended claims, without departing from the spirit of this invention; it is to be understood, therefore, that this invention is not to be limited to the specific details shown and/or described.

Having thus described the invention what is claimed is:

1. The process of forming the heel seat of a shoe having a turned-over upper, comprising, applying a localized heavy forming pressure and high heat to a narrow band on the outside margin of the upper where it turns over, to an extent and at a temperature sufficient to form and set the upper along that narrow band for the reception of the margin of a heel.
2. The process of forming the heel seat of a shoe having a turned-over upper, comprising, applying a forming pressure and heat to the turned-over upper to an extent and at a temperature sufficient to form and set the turned-over upper, there being applied a direct heavy localized forming pressure and high heat to a narrow band on the outside margin upper where it turns over to provide a narrow solid seat for the margin of the heel, the inside plaited margin of the upper being pressed down to flatten the plaits for the reception of the heel part inside of that margin.
3. The process of forming the heel seat of a shoe having a turned-over upper and having a sole part overlying the heel seat, comprising, applying a heavy forming pressure and high heat to the turned-over upper and directly to the sole part to an extent and at a temperature sufficient to form and set the turned-over upper and sole part for the reception of a heel.
4. The process of forming the heel seat of a shoe having an upper turned-over an insole at the heel and having a sole part overlying the heel seat and part of the turned-over upper, comprising, applying a heavy forming pressure and high heat to the outside margin of the turned-over upper adjacent the overlying sole part to an extent and at a temperature sufficient to form and set a narrow band on the outside margin of upper where it turns over to form a seat for the reception of the margin of a heel.
5. The process of forming the heel seat of a

shoe having a turned-over upper and having a sole part overlying the heel seat, comprising, applying a heavy forming pressure and high heat directly to the sole part, to a narrow band on the outside margin of the overlying upper and to the inside plaited margin of the over-turned upper, to an extent and at a temperature sufficient to form and set the materials for the reception of a heel.

6. The process of forming the heel seat of a shoe having a turned-over upper and having a sole part overlying the heel seat, comprising, applying a heavy forming pressure and high heat directly to the sole part at the breast line to an extent and at a temperature sufficient to set the material and form a shoulder at the breast line for the reception of a heel.

7. The process of forming the heel seat of a shoe having a turned-over upper and having a sole part overlying the heel seat, comprising, applying a heavy forming pressure and high heat directly to the sole part at and back of the breast line to an extent and at a temperature sufficient to set the material and form a shoulder at the breast line for the reception of a heel.

8. An apparatus for forming the heel seat of a shoe having a turned-over upper, comprising, a forming die having a rim adapted to engage the outside margin of the turned-over upper along a narrow band, means for applying high heat to said die, and means for applying high pressure to said die and localized at its rim while at a high temperature sufficient so as to form and set a narrow band on the upper where it turns over for the reception of a heel.

9. An apparatus for forming the heel seat of a shoe having a turned-over upper, comprising, a forming die having a rim adapted to engage the outside margin of the turned-over upper along a narrow band and having an inside part to engage the inside plaited margin of the upper, means for applying high heat to said die, and means for applying high pressure to said die and localized at its rim while at a high temperature sufficient so as to form and set a narrow band on the upper where it turns over and to press down and flatten the plaits for the reception of a heel.

10. An apparatus for forming the heel end of a shoe having a sole part overlying the heel seat, comprising, a forming die having a part adapted to engage the sole part; means for applying high heat to said die, and means for applying such high pressure to said die while at a high temperature sufficient so as to form and set the sole part for the reception of a heel.

11. An apparatus for forming the heel end of a shoe having a sole part overlying the heel seat, comprising, a forming die having a part adapted to engage and sink into the heel part at the breast line, means for applying high heat to said die, and means for applying such a high pressure to said die while at a high temperature sufficient so as to form and set a shoulder at the breast line for the reception of a heel.

12. An apparatus for forming the heel end of a shoe having a sole part overlying the heel seat, comprising, a forming die having a part adapted to engage and sink into the sole part at the breast line and engage the sole part back of the breast line, means for applying high heat to said die, and means for applying such a high pressure to said die while at a high temperature sufficient so as to form and set the sole part with

- 1 a shoulder at the breast line for the reception of
2 a heel.

3 13. An apparatus for forming the heel end of
4 a shoe having a turned-over upper and having a
5 sole part overlying the heel seat, comprising, a
6 forming die having an inside part adapted to en-
7 gage the sole part and having a rim part adapted
8 to engage the turned-over upper, means for ap-
9 plying high heat to said die, and means for ap-
10 plying such high pressure to said die while at a
11 high temperature sufficient so as to form and set
12 the turned-over upper and the sole part for the
13 reception of a heel.

14. An apparatus for forming the heel end of a
15 shoe having a turned-over upper and having a
16 sole part overlying the heel seat, comprising, a
17 forming die having an inside part adapted to en-
18 gage the sole part, having a middle part adapted
19 to engage the inside plaited margin of the turned-
20 over upper and having a rim part adapted to
21 engage the outside margin of the turned-over
22 upper along a narrow band, means for applying
23 high heat to said die, and means for applying
24 such high pressure to said die while at a high
25 temperature sufficient so as to form and set the
26 turned-over upper and the sole part for the re-
27 ception of a heel.

28 15. The process of forming the heel seat of a
29 shoe having a sole part overlying the heel seat,
30 comprising, marginally reducing the sole part at
31 the heel seat, and applying a heavy forming pres-
32 sure and high heat directly to the marginally
33 reduced sole part to an extent and at a high tem-
34 perature sufficient to set the material to a con-
35 formation suitable for the reception of a heel.

36 16. The process of forming the heel seat of a
37 shoe having a sole part overlying the heel seat,
38 comprising, marginally reducing the sole part at
39 the heel seat back of the breast line, and applying
40 a heavy forming pressure and high heat directly
41 to the sole part at the breast line to an extent
42 and at a temperature sufficient to set the material
43 and form a shoulder at the breast line for the
44 reception of a heel.

45 17. The process of forming the heel seat of a
46 shoe having a sole part overlying the heel seat, comprising, marginally reducing the sole part at the heel seat and along the breast line to form shoulders at the ends of the breast line, and applying a heavy forming pressure and high heat directly to the sole part at the breast line to an extent and at a temperature sufficient to set the material and form a shoulder on the sole part in line with said shoulders for the reception of a heel.

47 18. The process of forming the heel seat of a
48 shoe having a turned-over upper and having a
49 sole part overlying the heel seat, comprising, marginally reducing the sole part at the heel seat, and applying a heavy forming pressure and high heat to a narrow band on the outside margin of the turned-over upper adjacent the overlying sole part, to an extent and at a temperature sufficient to form and set the upper along that narrow band to form a seat for the reception of a heel.

50 19. The process of forming the heel seat of a
51 shoe having a turned-over upper and having a
52 sole part overlying the heel seat, comprising, marginally reducing the sole part at the heel seat, and applying a heavy forming pressure and high heat to a narrow band on the outside margin of the upper where it turns over and to the inside plaited margin of the over-turned upper, to an extent and at a temperature sufficient to form and set the upper along that narrow band and to press down and flatten the plaits for the reception of a heel.

53 20. The process of forming the heel seat of a
54 shoe having a turned-over upper and having a sole part overlying the heel seat, comprising, marginally reducing the sole part at the heel seat, and applying a heavy forming pressure and high heat to the margin of the over-turned upper and directly to the sole part to an extent and at a temperature sufficient to form and set the materials for the reception of a heel.
